BLANK REGISTERING DEVICE

William Ward Davidson, Evanston, Ill.

Application September 6, 1939, Serial No. 293,553

15 Claims. (Cl. 271—48)

The invention relates to the registering of blanks before they are fed to a machine, such as a printing press.

Conveyor boards are used with printing machines which, in the due course of business of a printer, handle blanks of different sizes. It is a prerequisite with printing machines that the blanks be brought into perfect registry before being delivered to the printing press, and, after being registered, to be delivered to the printing press in timed relation with the operation of the press.

The devices heretofore used in registering blanks of different sizes and thicknesses require complicated adjustments and settings which take up time whenever the conveyor board is being set up to feed a stack of blanks of a different form or size than that handled previously. Moreover, further adjustments have to be made while the devices are in operation.

Proper registry requires three operations. One of the operations is to end register the blank with regard to the feed pickup of the printing press. The second operation is registering the blank laterally so that the blank not only reaches the press at the proper moment but also enters the press correctly aligned. The third operation is the final feeding of the blanks to the press.

The third operation, the feeding operation, is done in the present invention as part of the first operation. The end registry is accomplished by providing stops constructed to operate as a unit with the feed mechanism. The stops temporarily engage the front edge of a blank to adjust it after which they are removed as part of the feeding cycle to release the blank in timed relation with regard to the operation of the press.

In carrying the blanks from a stack to the press, a plurality of tapes are generally used which convey the blank against the registry stops under friction drive engagement with the blank. In the present invention, an improved means is provided whereby blanks so moved are side registered in timed relationship with both the end registry by the stops and the release of the stops.

It is a further purpose of the invention to provide a side registering means which is simple in construction and easily adjusted that can be used with blanks of different sizes with a minimum amount of resetting needed to prepare the conveyor board for any given run of blanks.

Another object of the invention is to provide an improved feed movement for a printing press or the like wherein the blank is kept in continuous movement until perfect registry is completed

and the blank is ready for delivery to the press.

These being among the objects of the present invention, other and further objects will become apparent from the drawings, the description relating thereto and the appended claims.

In the drawings:

Fig. 1 is a top plan of a conveyor board illustrating the preferred embodiment of the invention,

Fig. 2 is a longitudinal section taken upon a vertical plane centrally through the structure illustrated in Fig. 1 showing a synchronizing mechanism by which end and lateral registry and release of a blank is accomplished in a preferred manner,

Fig. 3 is a view similar to Fig. 2 showing the construction by which the blank is withdrawn from the conveyor table after registry,

Fig. 4 is a transverse section through the conveyor board showing structural details of the means by which the side registry of the blank is accomplished;

Fig. 5 is a section taken transversely of the conveyor board showing one of the constructions by which the side registering means is adjusted,

Fig. 6 is a diagrammatical representation of the cam and follower controls as they are employed in the invention as located in their respective positions, and

Fig. 7 is an analytical view of the cams wherein the followers are located all at one point so that the timing and relative action of the cams may be better understood.

Referring now to the drawings in further detail the invention will be described first with reference to the general organization and general operation; second, to the special details and characteristics of the elements making up the assembly; and finally to a detailed description of the operation of the invention as a synchronized unit.

As viewed in Fig. 1, blanks are placed upon the conveyor table 10 at the left end thereof to be carried by tapes 11 toward and against stops 12.

In its forward movement, each blank comes close to or into contact with the side guide 13. At approximately the time each blank reaches the stops 12, the guide is jogged or advanced inwardly against the adjacent side of the blank by a jogging mechanism 14 as driven by a cam and follower assembly 15. When the guide 13 reaches the limit of its movement toward the blank, a gripper roller 16 is lowered against a feed roller 17 to remove the blank from the conveyor board at the right end thereof.

The conveyor board in its general construction, as more particularly described in Patent No. 2,083,296, issued to Nils Trydal, June 8, 1937, comprises two side frame members 20 secured in spaced relation to each other by transverse rods 21. The tapes 11 are endless ones as carried by rollers 22 journaled at opposite ends in the side frames 20.

The rollers 22 are driven by a belt and pulley assembly 23 which receives power and speed through a pulley 24 geared to the printing press shaft 25. The rollers 22 are journaled in the side frame members 20 parallel to each other but with their axes preferably extending slightly diagonal to the side frames so that the tapes 11 carry the blanks sideways as well as forwardly. Proper tension upon the tapes 11 is maintained by means of tension pulleys 26 mounted on the lag rod 27 which is pivoted to the frame members as at 28 upon arms 30.

The guide 13 is mounted upon the conveyor at that side thereof toward which the blanks are carried in their lateral movement by the diagonal pitch of the rollers 22. The guide 13 comprises an upstanding flange 31 serving as a guide rail and a horizontal plate 32 over which one of the tapes 11 slides when the conveyor is in operation. The guide 13 is disposed longitudinally of the conveyor board 10 as supported by spaced horizontally disposed studs 33 brazed to the flange 31. The studs 33 extend through a support bar 34 beyond which they receive knurled nuts 35.

Compression springs 36 are located upon the bolts 33 between the flange 31 and the nuts 35 to urge separation of the guide member 13 from the supporting bar 34 in a way which will yield if excessive force is brought to bear against the guide flange 31. By adjusting the nuts 35, the angularity or parallelism between the support member 34 and the guide member 13 can be adjusted to take care of different blank requirements.

The support bar 34 is secured to a block 37 by machine screws 38 and the block 37 in turn is supported upon a transverse rod 40 and secured thereto by a knurl-headed lock bolt 41. The transverse rod 40 is slidably mounted at both ends relative to the side frame members 20 for reciprocal axial movement in which the guide member 13 is oscillated horizontally to side register the blanks upon the conveyor table.

The rod 40 may be actuated axially from either end depending upon the most convenient place to locate the cams and the controls. In the view shown in Fig. 1, I prefer to actuate the guide member 13 with the cam arrangement 14 preferably located upon the guide side of the table.

In mounting the rod for reciprocation, the rod is supported at the side frame member 20 opposite the guide 13 upon a yoke 42 slidably mounted on two parallel pins 43 secured to the frame member 20 by nuts 44. The pins 43 prevent relative rotation of the rod 40 and a tension spring 45 urges the rod 40 to its advanced position in which the guide 13 registers the edge of the blank.

At the guide side of the frame (Fig. 4), the rod 40 extends through an aperture 46 in the frame member 20 beyond which it receives a sleeve 47 in loose relationship. Beyond the sleeve the rod 40 receives a lock collar 48 which carries thereon a follower 50 engaging the cam face 51 upon a thrust rod 52 which is supported for sliding relationship in a transverse groove 53 upon the sleeve 47.

The relationship of the cam and follower is such that the groove 53 in the sleeve as backed by the frame 20 supports the rod 52 so that a thrust upon the rod 52 forces the cam incline 51 between the follower and the groove 53 like a wedge to move the rod 40 against the action of the spring 45, this movement retracting the guide 13 from its blank registering position. In the embodiment illustrated in Fig. 1, the guide 13 is shown in its 10 advanced position.

As shown in Fig. 2, actuation of the thrust rod 52 and the cam 51 is accomplished by means of an arm 54 serving as a third class lever pivoted at one end to the frame 55 of a press 56. The rod 52 engages the other end of the arm 54 and the arm 54 is driven at a point intermediate its ends where it carries a follower 57 held against the cam 58 by a tension spring 60. The cam 58 is mounted upon the shaft 25 which is driven in direct relationship from a printing press, as already indicated.

The fact that the guide when moved toward the blank is moved by springs that will yield if there is an unexpected force preventing movement of the guide in that direction prevents the guide from being subjected to undue strain when it is performing its registering action. The springs and construction shown are arranged with this thought in mind.

On the other hand, retraction of the guide is positively had by an unyielding drive wherein all the elements involved are positively linked together. In this way the danger of unforeseen occurrences arising which would cause damage to the side guide when it makes its blank registry are removed and the guide is positively removed from its registering position after performing its function so that the next blank to be fed against the stops 12 is positively cleared of any hindrance from the guide if it would ever be retarded in its action for any reason.

In releasing the blank and feeding it to the press, the stops 12 are mounted upon the same shaft 61 which carries the feed roller 17. In this 45 way, the stops 12 are automatically and simultaneously removed from position the moment the feed of the blank is taken over by the feed roller 17.

Actuation of the feed roller is had through a gear 62 mounted at one end of the shaft 61. The gear 62 is rotated by a gear segment 63 at one end of an arm 64 which is actuated near its center by a cam 65 driving a follower 66 carried by the arm 64. The arm 64 is pivoted to the press at 67 at its other end and whenever the cam 65 releases the follower 66, the shaft 61 is returned to its original position by a torque spring 68 terminally engaging a lug 70 upon the frame member 55 and a lock collar 71 upon the shaft 61. The resting position for the shaft 61 is that in which the stops 12 are in blank engaging relation. With this arrangement, an overdriving.

In order for the feed roller 17 to act positively upon a blank, the grip roller 16 is formed as a loose pulley supported upon a yoke 72 carried by a shaft 73 that is actuated as best shown in Fig. 3 by means of an arm 74. The arm 74 is rigidly secured at one end to the shaft 73 with a follower 75 located at the other end driven by a cam 76 mounted on the shaft 25.

In Fig. 6, the cams 58, 65 and 76 are shown as superimposed upon each other in their true relation as mounted upon the shaft 25. Comparison with Figs. 2 and 3 will show that the respective followers of the cams are shown as

they are located relative to each other in the invention.

In Fig. 7, the cams and their respective followers are diagrammatically shown as rotated relative to each other so that the axes of the followers lie within a single straight radial line 77, so that a better understanding of the timing of the cams may be had.

In the timing of the cams, a blank is fed to the printing machine each revolution of the shaft 25 and the conveyor board is so adjusted and operated that a blank is removed from a stack and advanced by the tapes 11 to reach the stops 12 when the cams and followers are rotated by the shaft 25 to their relative positions indicated by the line 78.

Although each cam and follower may be adjusted relative to each other and the cams and followers to one another to take care of different conditions that may exist with different printing presses, I prefer to relate them as shown in Fig. 7 where within the first 32° of rotation of the shaft 25 after the blank reaches the stops 12, the guide cam 65 and follower 66 move the guide to the position shown in Fig. 1. During this time and simultaneously therewith the gripper cam 76 and follower 75 lower the gripper roller 16 to gripping position, the gripping relation being culminated immediately after the guide has advanced to its full register limit.

At the end of the next 25°, actuation of the feed roller cam begins and the guide is retracted. This feeding action continues for the next 82° turn in the shaft 25 to complete the positive feeding operation, after which the grip roller cam releases the grip roller to permit the remaining portion of the blank to move freely as drawn by the printing couple during the next 64°.

At this time, as far as the conveyor board is concerned, the feeding operation has been completed and it remains only to return the respective parts to their resting position to receive the next blank. The gripper roller 16 has already been raised and the guide 13 retracted and it remains only to have the feed roller follower 57 make the return upon the declining face 80 while the shaft 25 completes its revolution.

In this way, I provide an improved registering and blank conveying means which lends itself well to simple adjustment when used with printing presses that may require different settings. Consequently, although a preferred embodiment of the invention has been shown and described herein, it will be apparent to those skilled in the art that various and further uses, modifications and changes may be made without departing from the spirit and substance of the invention, the scope of which is commensurate with the appended claims.

What is claimed is:

1. The method of feeding a blank to a printing machine or the like comprising moving independent blanks successively laterally in one direction and forwardly against end stops and simultaneously moving the blanks laterally in the opposite direction by side engagement at one side only as one continuous movement of the sheet, clamping each blank in its registered position, and positively removing each and releasing the stops simultaneously in timed relation to the action of the printing machine.

2. The method of locating a blank of paper in proper registry comprising advancing a blank slightly sideways towards a movable side guide and forwardly against end stops, engaging the

blank with the moving side guide at approximately the time the blank reaches the stop so that the blank is under continuous movement until end registry and side registry are completed, thereafter forwarding the blank in timed relation to a machine processing the blank.

3. In a device of the class described having spaced side frames, a transverse rod slidably supported at one end upon one frame for longitudinal movement and slidably supported against relative rotation upon spaced lugs at the other end, a guide member carried by the rod, means for urging the guide member and rod to advanced position, and cam means for moving the rod in the opposite direction.

4. In combination, a blank conveying board for moving blanks one at a time longitudinally and laterally, releasable stop means for interrupting longitudinal movement of each blank at a predetermined point of registry, means for releasing said stop means, and resiliently urged means for opposing and reversing said lateral movement of the blank in timed relation with said releasing means to locate the blank laterally with respect to the conveyor board.

5. In combination, means for advancing a blank forwardly and laterally, means for locating the forward edge in end-registered position, a guide element at one side of the blank, a member adjustably supporting and resiliently urging the guide member to occupy its advanced position for moving the blank laterally into side-registered position, feed release means for removing said edge locating means, positive pull-out means engaging the blank for moving the blank from beside the guide element, and means for retracting the guide element after engagement of said pull-out means preparatory to receiving another blank for registry purposes.

6. In a device of the class described having spaced side frames, a transverse member slidably mounted upon the frames and supported against relative rotation, a guide member carried by said transverse member urged normally to advanced position, cam means for retracting said guide member, a gripper roller cooperating with a feed roller having registering stops, and means for synchronizing the operation of the gripper and feed roller with the cam means.

7. In combination with a printing press employing a feed mechanism having a predetermined cycle of operation, a conveyor comprising means for advancing a blank forwardly and laterally into engagement with said feed mechanism, a guide member for moving the blank sideways in a direction opposite said lateral movement, and means for synchronizing the operation of said guide with the operation of said feed mechanism.

8. In combination with a printing press employing a feed mechanism having a predetermined cycle of operation, a conveyor comprising means for advancing a blank forwardly and laterally into engagement with said feed mechanism, resiliently urged guide means for moving the blank sideways in a direction opposite said lateral movement, and means for synchronizing the operation of said guide with the operation of said feed mechanism.

9. In a device of the class described, means for conveying a blank forwardly and laterally, stop means for registering said blank in its forward movement, and resiliently advanced guide means for registering the blank laterally, a feed roller carrying said stop means, a gripper roller

cooperating with the feed roller, cam means for advancing the guide member, cam means for moving the gripper roller into gripping engagement with the blank, cam means for actuating the feed roller, and means for synchronizing the operation of said cam means in which the following sequence of operation is accomplished; advancing the guide member over a portion of its movement after the blank has engaged the stops, actuating the gripper member to engage the blank over a portion of its cycle after the blank engages said stops, actuating the feed roller to remove the stops and feed the paper to the printing press simultaneously with the retraction of the guide member and the gripper member.

10. The method of locating a sheet of paper in proper registry comprising moving the sheet forwardly and slightly sidewise to a predetermined release point in readiness for feed purposes, permitting the sheet universal planar movement and simultaneously moving the sheet in the opposite direction to registered position by side engagement at one side, and clamping the sheet in its registered position preparatory to its feed movement into the sheet processing machine.

11. The method of conveying blanks into feed registry for a printing machine or the like comprising separating the blanks one at a time from a stack near the printing machine, moving each blank separately forwardly and slightly sidewardly in its own plane and towards a movable side guide, continuing the movement of each blank thereafter in a universally supported relationship for any movement in the plane thereof, and moving each blank laterally in the opposite sideward direction as the blank reaches its end registry position, clamping each blank in its registered position, and positively removing each blank in timed relation to the action of the printing machine.

12. In a device of the class described having spaced side frames, a transverse rod slidably supported at one end with regard to one frame for longitudinal movement, and slidably supported against relative rotation at the other end by parallel guideways carried by the other frame, a sheet registering member carried by the rod, means for urging the member and rod in ad-

vanced position; and means engaging the rod to release the rod for movement in said urged direction and positively retracting the rod from its urged position.

13. In combination with a blank pull-out means for a printing press, means for conveying the blank forwardly at a predetermined speed, removable stop means for squaring and end-registering the blank, retractable guide means

10 for side-registering the blank, means for actuating said pull-out means, stop means and side guide means including elements synchronized in timed relationship to advance and hold the guide in register and remove the stop means from the path of the blank while said guide is in said register position.

14. In combination with a blank pull-out means for a printing press, means for conveying the blank forwardly at a predetermined speed, 20 stop means for squaring and end-registering the blank, guide means for side-registering the blank, means for actuating said pull-out means, stop means and guide means, and including elements synchronized to remove the stop means from the path of the blank in timed relationship with the operation of said printing press to advance the guide means to register position at approximately the time the blank is squared by the stop means and retract the guide means after the removal of the stop means, and feed means for gripping the blank while held in registered position.

15. In combination with a blank pull-out means for a printing press, means for conveying the blank forwardly at a predetermined speed, 30 removable stop means for squaring and end-registering the blank, retractable guide means for side-registering the blank, means for actuating said pull-out means, stop means and said guide means including elements synchronized in timed relationship to advance and hold the guide in register position and so constructed and arranged as to engage and move the blank into register position in one continuous movement of said forwardly conveying means at the end thereof, and remove the stop means from the path of the blank while said guide is in said register position.

WILLIAM WARD DAVIDSON.
